CLAIM

The ornamental design for an automobile, as shown and described.

DESCRIPTION

FIG. 1 is a front and right side perspective view of an automobile showing our new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof; and,
FIG. 7 is a top plan view thereof.

The broken lines in the drawings shown represent portions of the automobile that form no part of the claimed design.
